UNITED STATES PATENT OFFICE

CHARLES HECTOR FELTHAM, OF PROVIDENCE, RHODE ISLAND

METAL BROOM OR BRUSH

Application filed June 3, 1930. Serial No. 459,039.

This invention relates to metal-bristled brooms and brushes for use as cleaning or sweeping implements and also as extinguishers for fighting grass and forest fires.

One object of the invention is to provide a broom or brush of the type specified which is more efficient and durable in use and practically indestructible when subjected to heat.

Another object of the invention is to provide an implement of the type specified adapted for economical manufacture with its elements assembled without the use of solder, screws, rivets or other extraneous parts liable to become loosened or deranged.

Another object of the invention is to provide an implement of the type specified having a head composed of interfitting sheet-metal members adapted to be locked in connected relationship to clamp the metal bristles in place.

Another object of the invention is to provide an implement of the type specified in which the metal bristles are mounted in staggered relationship with their flat sides inclined with respect to each other to provide an overlapping arrangement thereof, whereby to effect greater compactness at their ends and a more impenetrable sweeping wall or edge.

Another object of the invention is to provide an implement of the type specified in which the bristles may be heat treated or hardened before applying them to the broom or brush to provide for greater strength and durability in use.

Further objects of the improvement are set forth in the following specification which describes a preferred form of construction of the implement, by way of example, as illustrated in the accompanying drawing. In the drawing:

Fig. 1 is a perspective view of a broom constructed in accordance with the present invention;

Fig. 2 is an enlarged cross-sectional view through the head of the broom illustrating its interfitting parts;

Fig. 3 is a front elevation of the broom, shown partly in section to illustrate the manner of telescoping the interfitting parts in co-

operative relationship and locking them in place;

Fig. 4 is a top plan view of the head of the broom showing the arrangement of the bristles therein; and

Fig. 5 is a perspective view of one of the looped bristles employed in the device.

This invention relates particularly to brooms, brushes or the like in which metal bristles or splints are provided as sweeping elements and consists in an improved construction and arrangement of the parts to effect a more efficient and durable implement for the purpose specified. In the embodiment of the invention as herein shown the implement comprises a hollow head constructed with a channel-shaped member having its base perforated to receive the legs of hairpin-shaped splints which serve as bristles. The channel-shaped member has means at its sides for supporting an auxiliary top-plate and for interconnection with an overlying cover. The legs of the splints are inserted through eyelets or apertures in the top-plate and base of the channel-member and clamped down by the cover to hold them fixedly in place. Means are provided at the ends of the top-plate cooperating with the ends of the cover to lock the various parts in connected relationship.

Referring to the drawing, as herein illustrated the head of the broom comprises a main member 2 constructed of sheet-metal folded into channel-shape to provide a bottom-plate 3 and upstanding sides 4. The bottom-plate 3 is perforated with eyelets or small holes 5, see Fig. 4, through which the legs of the metal bristles 15 extend downwardly in the manner as later explained. Only two rows of bristles 15 are shown in the drawing, but it is to be understood that a greater number may be provided if desired in accordance with the uses to which the implement is to be put.

The upwardly extending sides 4 of the channel-member 2 are provided with a series of ears or lugs 6 bent inwardly at right-angles thereto to form rests on which the top-plate 10, to be later described, is seated. Lateral flanges 7 formed as extensions of the sides 4

are bent outwardly and downwardly in overlying spaced relation thereto, thus providing guideways or grooves 8 in which the sides of the overlying cover 20 are held to connect the parts in the manner as later more fully explained.

The rectangularly-shaped top-plate 10, previously mentioned, is punched from sheet-metal stock and perforated with holes 11 through which the legs of the hairpin-shaped bristles 15 are passed in assembling the device. Tabs or projections 12 are formed integral with the ends of the top-plate 10, being adapted to be bent over the ends of the cover 20 to secure the members in connected relationship in the manner as later explained.

The cover 20 is also constructed from sheet-metal stock to form an inverted trough-shaped member having downwardly extending side-flanges 22. The sides 22 are folded inwardly and then projected upwardly to provide splines or runners 23 adapted to slide in the guideways 8 at the sides of the bottom-member 2 to interconnect these parts, the method of assembling the complete device being as next explained.

The sides 4 of the channel-member 2 are initially spread apart and the top-plate 10 placed in overlying relation to its bottom-plate 3. The legs of the wire splints 15 are then passed downwardly through the alining apertures 5 and 11 in the two plates. After this is accomplished the top-plate 10 is lifted within the channel-member 2 and the sides 4 thereof sprung inwardly to engage the lugs 6 in under its lateral edges as shown in Fig. 2.

It will be noted by reference to Fig. 4 of the drawing that the apertures 5 and 11 are so disposed that the bristles of the two opposite rows will be arranged in opposite angular relationship, that is inclined one with respect to the other and staggered along the length of the head. The cover 20 is next applied to the head by inserting its runners 23 in the guideways 8 at the top of the channel-member 2 and sliding it therealong until the ends of the two members coincide. During the sliding movement of the cover 20 its under side rides over the looped ends of the bristles 15 and acts to force them downwardly to clamp them in place in the head. With the cover 20 thus positioned on the channel-member 2 the projections or tabs 12 on the top-plate 10 are bent upwardly over the ends of the cover to lock it in place. If desired, the tabs 12 may be spot-welded to the top of the cover 20 to effect a permanent joinder of the parts.

Any suitable means may be provided for attaching a handle to the head of the broom and, as herein shown, a socket 25 is employed with the end of a metal tubular rod 30 inserted thereinto and welded in place. The socket 25 may be made in two parts, each section 26 having a half-tubular upstanding

portion stamped from sheet-metal with a lower lug 27 adapted to fit against the top of the cover 20 and a lateral ear 28 overlapping the side thereof. The lugs 27 and 28 are spot-welded to the cover 20 as at 29 and 31.

It will be observed from the foregoing that my invention provides a particularly staunch and sturdy implement for the purposes specified. The various parts of the broom or brush are constructed of heat-resisting and non-corrosive metal and assembled without the use of solder, screws, rivets or other parts liable to become loosened or deranged. The interfitting elements of the head provide for greater rigidity and strength and the staggered and angular arrangement of the bristles gives a more compact and closely spaced disposition of their ends to provide a more efficient sweeping edge. The angular arrangement of the bristles also results in greater stiffness or rigidity of their legs and prevents bending or distortion thereof. Due to its method of construction, the broom is practically indestructible and proof against damage when used for extinguishing fires. The bristles may be made of spring-steel, and separately hardened whereby to insure greater stiffness and durability in use. Because of its non-absorbent qualities the broom is rendered more sanitary, being easily cleaned in boiling water without injuring the bristles.

My improved broom or brush, being fire-proof, is particularly well adapted for use in coke-plants, boiler-rooms, foundries and other similar locations. The improved broom may also be used successfully for extinguishing grass and brush fires, the resilient bristles acting to kick up the dirt and spread it to smother the flames. It may be used with equal success in cleaning rough surfaces such as paved streets, concrete walks, wharf-planking and the like. Due to its impervious qualities it may also be used to advantage in dye-houses, slaughter-houses, fertilizer-plants, for sweeping liquids, sludge, and wet refuse and for various other purposes.

While I have herein shown and described a preferred form of construction of the improved implement it is to be understood that various modifications may be made in the structure and arrangement of its parts without departing from the spirit or scope of the invention. Therefore, without limiting myself in this respect, I claim:

1. An implement of the type specified comprising a head having a top-plate and bottom-plate disposed in opposite spaced relationship and provided with alining apertures, hairpin-shaped splints arranged with their legs extending through the apertures in both plates and projecting from the head in the form of bristles, a member overlying the top-plate and engaging against the looped ends of the splints to secure them in place in

the head, and means on said member and the head slidably engageable to secure the parts in permanent connection.

2. An implement of the type specified comprising a head constituted by a top-plate, opposite sides and a bottom-plate spaced below the top-plate with alining apertures in said top- and bottom-plates, hairpin-shaped splints arranged with their legs extending through the apertures in said plates and projecting from the head to provide bristles, a cover overlying the top-plate and engaging against the looped ends of the splints to hold them in place in the head, and means on the cover and the sides of the head adapted to interlock to secure the parts in permanent connection.

3. An implement of the type specified having a head comprising a channel-shaped bottom-member provided with apertures in its base and formed with grooves extending longitudinally of its sides, a top-member resting across the sides of the channel-member and provided with apertures substantially corresponding with those in the base thereof, hairpin-shaped splints arranged with their legs projecting through the apertures in the upper member and base of the channel-member, and a cover overlying the top-member and engaging against the looped ends of the splints, said cover having means adapted to interlock with the grooves on the sides of the channel-member to hold the parts in permanent connection with the splints projecting from the bottom of the head in the form of a brush or broom.

4. In an implement of the type specified, the combination of a channel-shaped member having its bottom provided with rows of spaced apertures and the upper edges of its sides folded over in overlying relation thereto, a top-plate extending between the sides of the trough-member and provided with apertures corresponding to those in the bottom thereof, hairpin-shaped splints arranged with their legs extending through the apertures of the top-plate and the bottom of the channel-member and projecting therebeyond in the form of bristles, and a cover-plate overlying the top-plate and provided with lateral flanges overlapping the sides of the trough-member and interengaging with the folded portions thereof, said cover-plate engaging against the looped ends of the splints to hold them in place.

5. In an implement of the type specified a head constructed with a channel-shaped bottom-member having rows of spaced apertures in its bottom, the upper portion of the sides of the channel-member being folded over to provide grooves, a top-plate extending between the sides of the channel-member in spaced relation with respect to the bottom thereof and provided with apertures corresponding to the apertures therein, hairpin-

shaped splints arranged with their legs projecting through the apertures in the top-plate and bottom of the channel-member, and a cover-plate extending across the top of the channel-member and provided with folded portions engaging the grooves at the sides thereof to secure the parts in connected relationship.

6. In an implement of the type specified, the combination of a head comprising a channel-shaped member having rows of spaced apertures in its bottom, a top-plate extending between the sides of the channel-member in spaced relation with respect to its bottom and provided with apertures corresponding to the apertures therein, hairpin-shaped splints arranged with their legs inserted through the apertures in the top-plate and the bottom of the channel-member and arranged in rows with the splints of adjacent rows inclined in opposite relationship, and a cover overlying the top of the channel-member and secured to the sides thereof to engage the loops of the splints to hold them in place in the head.

7. In an implement of the type specified, the combination of a hollow head comprising a channel-shaped member formed with rows of spaced apertures in its bottom and having its upper edges folded over in overlying relation to its sides, a top-plate extending between the sides of the channel-member and provided with apertures corresponding to the apertures in the bottom thereof, hairpin-shaped splints arranged with their legs extending through the apertures in the top-plate and the bottom of the channel-member, and a cover-plate resting across the top of the channel-member in engagement with the looped ends of the splints and having lateral flanges folded downwardly and inwardly to engage over the edges of the folded portions of the channel-member to secure the parts in connected relationship.

8. In an implement of the type specified, the combination of a hollow head comprising a channel-member having rows of spaced apertures in its bottom, the upper edges of the sides of said channel-member being folded over in overlying relationship to provide grooves extending longitudinally thereof, lugs extending inwardly from the sides of the channel-member, a top-plate resting across said lugs and provided with apertures corresponding to the apertures in the bottom of the channel-member, hairpin-shaped splints of flat wire arranged with their legs extending through the apertures in the top-plate and bottom of the channel-member, a cover-plate resting across the top of the channel-member and provided with lateral portions folded inwardly to adapt them to slide in the grooves on the sides of the channel-member whereby said cover-plate may be slid into position to hold the splints in place in the head, and means engaging the ends of the

cover to secure the latter in fixed position on the head.

9. In an implement of the type specified, the combination of a hollow head comprising a channel-shaped member provided with rows of spaced apertures in its bottom, a top-plate extending between the sides of the channel-member and provided with apertures corresponding to those in the bottom thereof, hair-pin-shaped splints arranged with their legs inserted through the apertures in the top-plate and bottom of the channel-member, a cover-plate resting across the top of the channel-member in engagement with the looped ends of the splints and having lateral flanges overlapping the sides thereof and secured thereto, a socket-member secured to the top of the cover-plate, and a handle held within the socket of said member.

10 20 In testimony whereof I hereunto affix my signature.

CHARLES HECTOR FELTHAM.
